CLAIM

The ornamental design for the “portable control panel for a video/graphics workstation”, as shown and described.

DESCRIPTION

FIG. 1 is an isometric view of a portable control panel for a video/graphics workstation in accordance with the invention;

FIG. 2 is a top plan view of a portable control panel for a video/graphics workstation in accordance with the invention;

FIG. 3 is an end view of a portable control panel for a video/graphics workstation in accordance with the invention;

FIG. 4 is an opposite end view of a portable control panel for a video/graphics workstation in accordance with the invention;

FIG. 5 is a bottom plan view of a portable control panel for a video/graphics workstation in accordance with the invention;

FIG. 6 is a side view of a portable control panel for a video/graphics workstation in accordance with the invention; and,

FIG. 7 is an opposite side view of a portable control panel for a video/graphics workstation in accordance with the invention.

The broken lines are shown in the views for illustrative purposes only and form no part of the claimed design.
